(57) **CLAIM**

The ornamental design for a housing for electrical conductor, as shown and described.

DESCRIPTION

1. Housing for electrical conductor

1.1 : Perspective

1.2 : Top

1.3 : Bottom

1.4 : Front

1.5 : Left

1.6 : Right

The broken line showing is for the purpose of illustrating portions of the housing for electrical conductor that form no part of the claimed design.

Conduit for cables having an at least partially inverted diamond-shaped cross section defining a pavilion face, a girdle and a crown.
